DESIGN FOR A WASHING MACHINE WRINGER

Fred A. Conterman, Jamestown, N. Y., assignor
to Blackstone Corporation, Jamestown, N. Y.,
a corporation of New York

Application March 7, 1941, Serial No. 99,410

Term of patent 7 years

To all whom it may concern:

Be it known that I, Fred A. Conterman, a citizen of the United States, residing at Jamestown, in the county of Chautauqua and State of New York, have invented a new, original, and ornamental Design for a Washing Machine Wringer, of which the following is a specification, reference being had to the accompanying drawing, forming part thereof; and in which

Figure 1 is a front elevational view of a washing machine wringer showing my new design;

Figure 2 is a plan view thereof; and

Figure 3 is an end elevational view, the wringer support being broken away for convenience of illustration.

I claim:

The ornamental design for a washing machine wringer, substantially as shown.

FRED A. CONTERMAN.
